US0D1018047S

(12) **United States Design Patent** (10) **Patent No.:** **US D1,018,047 S**
(45) **Date of Patent:** **** Mar. 19, 2024**

(54) **STACKABLE STORAGE UNITS**

(71) Applicant: **Li Zhang**, Chengdu (CN)

(72) Inventor: **Li Zhang**, Chengdu (CN)

(**) Term: **15 Years**

(21) Appl. No.: **29/905,795**

(22) Filed: **Oct. 26, 2023**

Related U.S. Application Data

(62) Division of application No. 29/881,142, filed on Dec. 28, 2022.
